UNITED STATES PATENT OFFICE.

JAMES L. THOMPSON, OF ALLEN, OKLAHOMA.

GATE-LATCH.

1,387,914.

Specification of Letters Patent. Patented Aug. 16, 1921.

Application filed November 12, 1920. Serial No. 423,600.

To all whom it may concern:

Be it known that I, JAMES L. THOMPSON, a citizen of the United States of America, and resident of Allen, in the county of Pon-toc and State of Oklahoma, have invented certain new and useful Improvements in Gate-Latches, of which the following is a specification.

This invention relates to gate latches and means for operating the same, and it has for its object the provision of novel means accessible from either side of a gate and effective to actuate a latch, the said latch and its operating mechanism being of simple construction and capable of being produced by the stamping process so that the cost of manufacture is comparatively small in view of the fact that no finishing work would be required.

10 A still further object of this invention is to produce a latch bolt which may be stamped from a single piece of metal, the same having latch engaging shoulders whereby the bolt may be operated; the said latch 15 being associated with guiding elements which may be likewise formed by the stamping process.

20 A still further object of this invention is to produce a latch of the character indicated 25 which will not be seriously affected either in its operation or condition by weather conditions and for that reason it will prove durable and efficient.

25 With the foregoing and other objects in view, the invention consists in the details of construction, and in the arrangement and combination of parts to be hereinafter more fully set forth and claimed.

30 In describing the invention in detail, reference will be had to the accompanying drawings forming part of this specification wherein like characters denote corresponding parts in the several views, and in which—

35 Figure 1 illustrates a view in perspective of a latch embodying the invention applied to a gate; a fragment of the gate being shown;

40 Fig. 2 illustrates a side elevation thereof; and

45 Fig. 3 illustrates a sectional view on the line 3—3 of Fig. 2.

In these drawings 10 denotes a post hav-

ing a latch engaging member 11 of a conventional type, the same being intended to be engaged by a latch bolt for holding a closure in closed position.

The closure 12 has guides 13 secured to it by fastenings 14 such as rivets, bolts or the like, the said guides being stamped from metal and shaped with end ears 15 and 16, it being possible to stamp and shape these guides at one operation under the well known stamping processes.

50 The latch or bolt 17 is preferably provided with reduced ends 18 and 19 fitting in the guides to slide therein, and preferably the central portion 20 of the bolt is offset outwardly as at 21 so that the said central portion clears the side of the closure to such an extent as to receive the end 22 of the operating lever 23 which lever is mounted on a stud or pivot 24 applied to the closure. The operator engaging end of the lever has an extension 25 preferably at right angles to the length of the lever, the said extension being doubled on itself and having an extremity 26 which projects across the end of the lever and by this construction, hand engaging projections are formed on either side of the closure so that a person approaching the gate from either direction may be able to manipulate the said lever.

55 A guide 27 is provided for the lever and it is of the same construction as the guides 13.

60 As shown, the latch engaging end of the lever is bifurcated and it embraces the upper edge of the latch and it bears against a shoulder 28 formed at the upper edge by recessing the said latch by a clearance extending inwardly from the edge. If desired, the device can be so made as to cause the lever to operate the latch in either direction, but preferably I supply the lever for retracting or releasing the latch from its engaging member and depend upon a spring 29 which enters an aperture 30 in the outer end of the latch to hold the said latch normally in engagement with the member on the post, and when this expedient is employed, the spring may comprise a single length of resilient wire anchored between studs or nails 31 above or below the latch at which point the resilient metal is bent at an angle to that portion which is in engagement with the latch, and the end or extrem-

2
ity of the said resilient material is anchored as at 32; hence a spring action results tending to hold the bolt in normal position.

From an inspection of the drawing it 5 would be apparent that in the manufacture of this device the bifurcated end of the lever may be produced and shaped as a part of the operation which forms and shapes the opposite end thereof, and hence, the operating lever as well as the bolt may be produced 10 by machinery from sheet metal.

Between the pivot 24 and the latch engaging part of the lever there is a quarter twist which causes the end of the lever to 15 stand approximately at right angles to the length of the bolt, and as the said end of the lever has a slot to receive the edge of the bolt, the said lever may be said to straddle the edge of the bolt and bear against the 20 shoulder thereof.

I claim:

1. In a gate latch, a guide adapted to be secured to the gate, a bolt having ends 25 slideable in the guide, the said bolt having recesses in its edge, the said recessed portion being offset with relation to the bolt, a bolt engaging member comprising a lever consisting of an elongated plate adapted to be pivotally connected to the closure and having the latch engaging end twisted with 30 relation to the said lever, the said latch engaging end being bifurcated to straddle the edge of the bolt and enter the recess thereof

to bear against the shoulder formed by the said recess, and means for holding the bolt 35 in normal position.

2. In a gate latch, a bolt having an offset portion between its ends, shoulders formed on the said offset portion, guides in which the ends of the bolt are slideable, a bolt operating lever comprising a plate having a twisted bifurcated end, means for securing the flat portion of the lever to the closure and holding the bifurcated end of the lever in engagement with the bolt, and means for 45 holding the bolt in normal position.

3. In a gate latch, a bolt having a shoulder in its edge and means for guiding the bolt, a lever comprising a plate having a twisted bifurcated end embracing the bolt 50 and bearing against the shoulder, and means for pivotally mounting the lever in operative relation to the bolt.

4. In a gate latch, a bolt having a recess in its edge forming a shoulder, the said recessed portion being offset with relation to the bolt, means for guiding the bolt, a lever comprising a plate having its end twisted with relation to the plate, the said twisted end being bifurcated to embrace the bolt in 55 the recess, the said plate having its opposite end shaped to form projections extending across the end of the lever, and means for 60 pivotally mounting the lever in operative relation to the bolt.

JAMES L. THOMPSON.
